United States Patent Office

Des. 185,880

Patented Aug. 11, 1959

185,880

BOTTLE

Walter F. Baker, Hidden Valley, Calif., assignor to Owens-Illinois Glass Company, a corporation of Ohio

Application August 21, 1958, Serial No. 52,323

Term of patent 14 years

(Cl. D58—8)

Fig. 1 is a side elevational view of a bottle showing my new design.

Fig. 2 is a fragmentary rear elevational view thereof; and

Fig. 3 is a top plan view thereof.

The characteristic feature of my design for the bottle disclosed resides in the handle portion thereof having the configuration shown.

I claim:

The ornamental design for a bottle, substantially as shown and described.
